BEVERLY C. GOODRICH AND ONE-FOURTH TO WALTER E. MOSS, BOTH OF
MEMPHIS, TENNESSEE.

COTTON GIN.

Application filed March 31, 1921. Serial No. 457,305.

To all whom it may concern:

Be it known that I, CHARLES R. WOOD, a citizen of the United States, residing at Memphis, in the county of Shelby and State 5 of Tennessee, have invented a new and useful Improvement in Cotton Gins, of which the following is a specification.

This invention has reference to cotton gins and is particularly designed for ginning long staple cotton.

The object of the invention is to provide means whereby the lint removed from the cotton seed is in turn stripped from the gin saws without damage to but actually 15 improving the cotton and without breaking or rupturing the lint and so destroying its long fiber character. The invention is also adaptable to short staple cotton without necessitating any change in the gin. In 20 conjunction with means for removing the lint from the saw teeth without damage to the lint, provision is made for separating motes from the lint before such lint passes into the lint condenser.

25 The invention contemplates the employment of a plurality of gangs of saws with each gang mounted on a hollow shaft and the several hollow shafts carried by a main shaft to which each hollow shaft is connected by a controllable clutch mechanism whereby the main or power driving shaft and one or more of the hollow shafts may be coupled together or disconnected from each other so that in the event of the stopping 30 of one or more of the gangs of gin saws, for any reason, the other gins may continue in operation without interruption.

The invention also contemplates the employment of certain mechanisms and structures to be hereinafter described and which are shown in the accompanying drawings forming part of this specification and with which the following detailed description is to be read for an understanding of the invention, but without confining the invention to any strict conformity with the showing of the drawings, for the invention may be changed and modified so long as such changes and modifications mark no departure 45 from the salient features of the invention as expressed in the appended claims.

In the drawings:

Fig. 1 is a side elevation with some parts

in section, of a cotton gin embodying the invention.

55 Fig. 2 is a front to rear vertical section of the structure shown in Fig. 1.

Fig. 3 is an inverted plan view with some parts in horizontal section of a gin embodying the invention.

60 Fig. 4 is a horizontal section through a group of nozzles for directing air against the teeth of the saws to remove lint carried thereby.

Fig. 5 is a face view partly in section of 65 the structure shown in Fig. 4.

Fig. 6 is a vertical section through one of the nozzles and adjacent parts.

Referring to the drawings, there is shown a frame 1 carrying bearings 2 for a hollow 70 shaft 3 carrying a gang of saws 4 with intervening space blocks 5. Through the hollow shaft there extends a solid shaft 6, which at one end carries a pulley 7 which may be taken as indicative of either a belt pulley 75 or a connection for an electric motor. At one end of each gin, of which there may be several in the battery, there is provided a friction clutch 8 to couple the power or solid 80 shaft 6 to the respective gin while the solid shaft 6 may extend beyond the last gin in the battery and be continued to drive the baling press, which latter, however, is not shown in the drawings.

The gin saws 4 are preferably formed 85 with teeth 9, each having its outer face curved on a radius substantially that indicated by the dotted line 9^a in Fig. 6 and an inner face curved on a shorter radius indicated at 9^b, the difference in radius causing 90 the inner and outer walls of the teeth to intersect, thereby producing an overhanging point with the entrance between the teeth considerably wider than the throats of the teeth, thus facilitating the stripping of the 95 cotton from the teeth. The reason for the particular curvature of the teeth or substantially such curvature is to engage the lint fibers without breaking them, to work on either dry or damp cotton, and the large 100 spacing of the teeth causing the teeth to gin faster.

In the breast of the gin between the saws are curved separating ribs 10 stopping short of the periphery of the saw near the roots 105 of the teeth. There is also provided a roll

box 11 receivig the cotton from the feeder to a mouth 12. Spaced from the upper end of the ribs 10 is a curved board 13, within the roll box, and this curved board 5 is slightly elevated above the points of the teeth and conforms to the curvature of the roll box. On the face of the board 13, which is concave, are series of curved fins 14, one fin for each saw, and shaped to cause a shifting 10 of the cotton lengthwise of the roll box, the movement of the cotton in the roll box being brought about by the action of the saws thereon, so that the saws progressively engage fresh spots in the roll as the latter 15 rotates in the roll box, and so ultimately the lint and all the cotton seed contained in the roll box. In this manner, the saw teeth engage the lint and carry it to the space between the ribs 10 and the roll box board 20 13, stripping the lint from the seed, which seed thereupon finds its way out of the bottom of the breast.

At the bottom edge of the curved or roll board 13, where adjacent to the teeth of the 25 saws, are the notches 15 over each saw to prevent the saw from striking the board, while at the same time permitting the approach of the lower edge of the board so close to the ribs 10 as to prevent the seed 30 from passing through the space 16 between the upper ends of the ribs 10 and the bottom of the board 13. The lint carried by the saw teeth is drawn through the space 16.

Supported by a beam 17 forming part of 35 the frame of the gin is an upright mote board 18 with its lower edge terminating above the path of the teeth 9 of the saws. Below the mote board 18 are mote ribs 19, each leaving a space 20 large enough to permit the lint 40 carried by the teeth of the saws to pass and also permit streams of air to flow therethrough in a direction opposite to the travel of the teeth, so as to blow motes from the lint approaching the openings 20, these motes 45 falling past the saws in the spaces between them to the floor or other point of disposal. The mote ribs 19 are carried by bars 21 fast in the frame of the gin. Back of the mote board 18 and ribs 19 in a nozzle pipe 22 connected at a suitable point or points by a duct 50 23 with a flue 24 coming from a suitable blower 25 driven by meshing gearing 26, 27, or in other appropriate manner, to the main line shaft 6.

55 Adjacent to the edge of each saw 4 where passing through the space 20 is a nozzle 28 shown more in detail in Figs. 4, 5 and 6 to which reference is particularly directed. Each nozzle 28, of which there is one for 60 each saw, has U-shaped walls 29, 30 extending to the lower end or outlet whereby the outlet is in the form of a U-shaped nozzle with the walls 29 shorter than the walls 30 and the latter bent toward each other and 65 toward the walls 30.

The teeth of the saw enter between the U-shaped walls 29 close to the mouth of the nozzle, carrying lint for a short distance along the nozzle and then into position to receive streams of air directed lengthwise 70 of the nozzle and of the portion of the saw traversing the nozzle, so that these streams of air will engage the lint carried by the saw. Each nozzle 28 is provided with a duct or passage 31 directing the air under 75 and on top of the cotton carried by the teeth and thereby stripping it from the saw. The wall 29 near the upper end has formed therethrough a slot or opening 32, best shown in Figs. 5 and 6, and overridden by a 80 tongue 33 directed toward the opening 20, so that the nozzle pipe also provides a stream of air for each saw in a direction opposite to the rotation of the saw and this stream of air flows through the opening 85 20 and blows any motes which may occur in the cotton carried by the saw away from the opening 20 thereby disposing of them, as previously described.

Carried by the nozzle pipe and by the 90 bar 21 are the walls of a conduit 34 connected to a main lint flue 35. When the saw teeth loaded with lint enter between the walls 30 of the nozzles, the lint is brought into contact with the side walls 30^a which causes 95 a loosening up and agitation of the cotton fibers on the teeth, thereby cleaning and facilitating the stripping of the cotton fibers from the teeth.

What is claimed is:—

1. In a cotton gin, a gang of gin saws, a 100 series of nozzles into which the teeth of the saw extend, and a nozzle pipe and blower flue feeding the nozzle pipe with air, each nozzle deepening with respect to the path of the teeth with the deep end of the nozzle constituting the air projecting end thereof on opposite sides of the saw teeth in the line of travel of the saw, whereby the air lifts the lint carried by the saw and strips it 105 from said saw.

2. In a cotton gin, a gang of gin saws, a 110 series of nozzles into which the teeth of the saw extend, and a nozzle pipe and blower flue feeding the nozzle pipe with air, each nozzle deepening with respect to the path of the teeth with the deep end of the nozzle constituting the air projecting end thereof on opposite sides of the saw teeth in the line of travel of the saw, whereby the air lifts the lint carried by the saw and strips it 115 from said saw, each nozzle being provided with means for directing a stream of air in the reversed direction to the travel of the lint where entering the nozzle to prevent motes from reaching the nozzle.

3. In a cotton gin, gin saws, and an air nozzle for each saw entered by said saw to a progressively deeper extent as the saw approaches the discharge end of the nozzle, 120

whereby the lint carried by the teeth is lifted and spread by the air stream and discharged from the teeth.

4. In a cotton gin, a gang of gin saws, a series of air nozzles each having a channel of U-shape and individual to a saw and entered by the saw teeth, said channel deepening in the direction of travel of the teeth, and means for supplying each channel with air under pressure.

5. In a cotton gin, a gang of gin saws, a series of air nozzles each having a channel of U-shape and individual to a saw and entered by the saw teeth, said channel deepening in the direction of travel of the teeth, and means for supplying each channel with air under pressure, each channel at its shallower end having a passage communicating with the air supply and directed 15
versely to the movement of the saw through

the nozzle and provided with a lip directed toward the saw teeth, whereby a stream of air blows against the lint carried by the saw teeth to prevent the entrance of motes into the nozzle.

6. In a cotton gin, rotatable gin saws, and a U-shaped nozzle for each saw extending in the direction of rotation of the saw teeth and gradually deepening, whereby the saw teeth loaded with lint enter between the 25
side walls of the U-shaped nozzle causing a loosening up and agitation of the cotton fibers on the teeth, thus cleaning the cotton and facilitating the stripping of the cotton fibers from the teeth by the air issuing from 30
the nozzle.

In testimony, that I claim the foregoing as my own, I have hereto affixed my signature.

CHARLES R. WOOD.
